UNITED STATES PATENT OFFICE

2,066,811

PORTABLE ELECTRIC LAMP

Grant Wheat, Marlboro, Mass., assignor to Kochler Manufacturing Company, Marlboro, Mass., a corporation of Massachusetts

Original application June 3, 1932, Serial No. 615,115. Patent No. 2,027,298 dated January 7, 1936. Divided and this application February 24, 1934, Serial No. 712,739

2 Claims. (Cl. 240—10.6)

This invention relates to portable electric lamps of the general type shown in certain of my prior patents. While lamp structures of this general character were developed originally for use by miners, they have gone into rather general use in other lines, either in approximately the forms illustrated in my patents, or in modifications embodying essentially the same ideas. They are ordinarily known as "miner's lamps".

10 In lamps of the commercial forms power is supplied by a storage battery which usually is slung from the wearer's belt, or is carried on some other part of the person. Such batteries must be charged at suitable intervals. In most mines it is the custom for miners to leave their lamps in the lamp house where they are placed on charge immediately after the miners have left the mine, and they take their lamps again before going into the mine. Because of the fact 20 that these lamps are designed primarily for use in mines where they must be expected to operate in explosive atmospheres, it is extremely important to prevent any possibility of a spark occurring either due to some incident in the normal operation of the apparatus, or due to the 25 mischievous tampering or experimenting with the lamp structure by the miners themselves. This introduces a problem in the charging of the batteries because of the desirability of having the 30 terminals located in some exposed or readily accessible position so that the batteries can quickly be placed on charge when they are left at the lamp house. To devise a thoroughly practical solution for this problem forms the chief object 35 of the present invention.

The nature of the invention will be readily understood from the following description when read in connection with the accompanying drawings, and the novel features will be particularly 40 pointed out in the appended claims.

In the drawings,

Figure 1 is a perspective view of a lamp structure embodying features of this invention;

Fig. 2 is a diagram of the circuit connections 45 of the apparatus shown in Fig. 1;

Fig. 3 is a plan view, with parts broken away, of the thermostatic switch in the headpiece shown in Fig. 5;

Fig. 4 is a sectional view of said thermostatic 50 switch;

Fig. 5 is a perspective view of the headpiece shown in Fig. 1, but with the bezel, lens, reflector and main lamp removed;

Fig. 6 is a view, partly in vertical section and partly in side elevation, of the headpiece shown in Fig. 1;

Fig. 7 is a vertical, sectional view of a battery casing top including certain of the control elements which are mounted in the headpiece of the construction shown in Fig. 1;

Fig. 8 is a perspective view of the rotating element of the switch shown in Fig. 13; and

Fig. 9 is a perspective view of a magnetic switch which may be substituted for the thermostatic switch shown in certain of the other figures.

Referring first to Fig. 1, the lamp structure there shown comprises a headpiece or lamp casing 2 equipped with a spring actuated clamping device 3 for gripping the edges of a metal plate 4 which is secured to the front of a miner's cap 5 so as to hold the headpiece securely on the cap. A cable 6, including suitable electric conductors, operatively connects this headpiece with a storage battery 7 slung from the wearer's belt 8.

Referring more especially to Figs. 5 and 6, it will be observed that the main lamp 10 is mounted in the headpiece immediately in front of a concave reflector 13. Preferably it consists of an incandescent electric lamp of a special type 30 having two filaments 16 and 17 and provided with two end terminals 18 and 19, respectively, these terminals being connected to the respective leading-in wires 20 and 21. The middle lead wire 22 is electrically connected to the metal base 14. 35 The connections for conducting current to this lamp comprise two leaf springs 24 and 25, secured in the headpiece, with their ends positioned to bear, respectively, on the two terminals 18 and 19. The lamp base is straddled by a forked 40 spring 26 having depressions in its arms to receive the pins 15 at opposite sides of the base. These springs 24, 25 and 26 exert a downward pressure on the lamp bulb, and it is supported against this pressure by a spring arm 27 secured 45 firmly to the casing and curved and forked at its forward end to partly embrace the lower end of the bulb 10, the construction being such that it tips this bulb backwardly against the reflector. 50 This construction is of value in breaking the en-

gagement of the terminals 18 and 19 with the contacts 24 and 25, in the event that the lamp bulb becomes broken.

The lamp structure also includes an emergency lamp bulb 12 located chiefly behind the reflector 13 and supported in a suitable socket.

In order to enable the operator to use either filament 16 or 17 of the main lamp, or to turn on the emergency lamp 12, as he may desire, 10 an electric switch is mounted in the headpiece and comprises a switch arm 33, Figs. 2 and 5, connected directly with the button 35, Fig. 1, mounted on the outside of the headpiece 2, the switch arm being arranged to engage the ends 15 of either of the contacts 24 or 25, or with another contact 34 which is connected with the spring contact of the emergency lamp socket. One terminal of the battery is connected to the switch arm 33, while the other is connected to the 20 those members which receive or engage the bases of the lamps 10 and 12.

For convenience in charging the battery, two charging terminals 51—51, Figs. 1 and 6, are located at opposite sides of the neck or shank of the 25 headpiece and in exposed positions, as shown in one of my earlier patents, and in order to prevent the miner from short-circuiting the battery simply by connecting these terminals with a wire, or some other conductor, they are connected to the 30 battery through a switch which not only is normally held open, but is entirely out of the miner's control. In addition, it is desirable to reduce the duties of the attendant at the lamp house and, in fact, to avoid the necessity for an attendant in 35 the lamp house of a small mine. Consequently, the present invention proposes not only to take the charging circuit out of the control of the miner, but also to provide such an arrangement that the miner can charge his own battery simply by placing it in the proper position in the 40 charging rack when he leaves the mine, and turning the switch to a given position.

Referring more particularly to Fig. 5, it will be seen that the switch arm 33, previously mentioned, is arranged to engage an additional contact 52 which is connected with one of the charging terminals 51. The switch 33 is continuously connected with one terminal of the battery while the other battery terminal is connected through 50 a thermostatic switch 53 to the other charging terminal 51. This switch is best shown in Figs. 3 and 4. It includes a bi-metallic strip 54 around which is wound a coil 55 of resistance wire. The strip carries a contact 56 adapted to engage a 55 stationary contact 57 which is carried by, but is insulated from, the switch base. A casing encloses the switch parts. Normally the bi-metallic strip 54 is warped or sprung to such an extent that it holds the contact 56 out of engagement with the contact 57 and, consequently, maintains the charging circuit open. As soon, however, as the lamp is properly placed in the charging rack a current flows from one charging terminal 51 through the resistance coil 55 and the thermostatic switch 54 back to the other charging terminal. This raises the temperature of the thermostatic switch and causes its free end to swing toward the stationary contact 57, thus closing the switch. If the manually operated switch 33 has 60 previously, or is now, moved to bring its arm 33 into engagement with the contact 52, a charging current then will flow through the battery 1. When the miner takes his lamp out of the charging rack in the morning, it is simply necessary for him to 65 turn the switch arm 33 far enough to light one 70

of the filaments 16 or 17, and he can then go to work. The bi-metallic strip 54 cools off rapidly and opens the thermostatic switch very shortly after the lamp has been removed from the charging rack.

This construction, therefore, enables the miner to recharge his own lamp, and in many mines makes it unnecessary to keep a man on duty at the lamp house.

Instead of using a thermostatic switch an electro-magnetic switch may be substituted for it. Such a construction is shown in Fig. 9. It includes a core 60 with an energizing winding 61 which is connected across the charging terminals in the same way that the resistance wire 55 is connected in the diagram shown in Fig. 2. Located within the field of this magnet is an armature 62 carrying a contact 63 arranged to engage cooperating stationary contacts 64. This switch 63—64 is connected in the charging circuit in the same way as the switch 56—57 in Fig. 2. Its operation is essentially the same. It is, however, slightly larger and heavier than the thermostatic switch, and the latter is preferred for this reason.

Instead of having the control units above described all mounted in the headpiece, it is possible to transfer some, or all of them, to the battery casing. Such an arrangement is illustrated in Figs. 7 and 8 in which the thermostatic switch 53 is connected to the charging terminals 55—55 in essentially the manner above described, these terminals, however, being mounted in the top of the battery casing. Also located in the casing top is a switch consisting of a rotary shaft 66 having a metal switch segment 67 arranged to electrically connect a central terminal 68 with either of two side terminals 69 or 70. In the position of the parts shown in Fig. 7, the two contacts 68 and 69 are electrically connected, and the battery is ready for the charging operation. When, however, the switch knob 66 is turned to electrically connect the contacts 68 and 70, the charging circuit then is broken, and the headpiece is electrically connected with the battery. Even when this arrangement is used, however, it is preferable to mount a switch on the headpiece for turning the current on to either of the filaments of the main lamp 10 or on to the emergency lamp 12, as circumstances may require.

The invention thus provides a portable lamp structure in which the charging of the battery is facilitated, while at the same time minimizing the danger of creating a spark or injuring the apparatus itself, either accidentally or through tampering by the miners.

While I have herein shown and described preferred embodiments of my invention, it will be understood that the invention may be embodied in other forms without departing from the spirit or scope thereof.

The present application is a division of my co-pending application Serial No. 615,115, filed June 3, 1932, which has matured into Patent #2,027,298, Jan. 7, 1936, the claims in the present case being limited to the construction provided to facilitate charging, while those in the parent case are directed to other features of the invention disclosed in the latter application.

Having thus described my invention, what I desire to claim as new is:

1. In a miner's lamp, the combination with a headpiece adapted to be secured to the miner's clothing, said headpiece including a casing, an electric lamp bulb mounted in said headpiece, a storage battery, a casing for said battery and cir-

cuit connections for operatively connecting said battery with said lamp bulb, of exposed charging terminals on one of said casings adapted to be connected with an outside source of current to charge said battery, a charging circuit for connecting said terminals with said battery, said charging circuit including a normally open switch located in one of said casings for maintaining said battery electrically disconnected from one of said terminals whereby the latter terminal is normally maintained electrically dead, a control circuit permanently connecting said charging terminals, and means in said control circuit arranged to be operated by the flow of current therethrough for operating said normally open switch to close it.

5. In a miner's lamp, the combination with a headpiece adapted to be secured to the miner's

clothing, an electric lamp bulb mounted in said headpiece, a storage battery, and circuit connections for operatively connecting said battery with said lamp bulb, of exposed charging terminals on said headpiece adapted to be connected with an outside source of current to charge said battery, a charging circuit for connecting said terminals with said battery, said charging circuit including a normally open thermostatic switch in the lamp for maintaining said battery normally disconnected electrically from one of said terminals, whereby the latter terminal is normally maintained in an electrically dead condition, and a control circuit for said switch permanently connecting said charging terminals and including a coil for heating the thermostatic element of said switch.
